UNITED STATES PATENT OFFICE.

ETIENNE OEHMICHEN, OF VALENTIGNEY, FRANCE.

CONTROLLING AND STABILIZING DEVICE FOR HELICOPTERS.

Application filed July 26, 1923. Serial No. 653,956.

To all whom it may concern:

Be it known that I, ETIENNE OEHMICHEN, a citizen of the Republic of France, and residing at Valentigney, Doubs Department, 5 Rue des Graviers, in the Republic of France, have invented certain new and useful Controlling and Stabilizing Devices for Helicopters, of which the following is a specification.

10 It is recognized that helicopters as a general rule possess no proper stability, so that devices must be used whereby the machine may be straightened when it becomes inclined, and it is further required to act 15 against the displacement of the center of pressure below the propellers when the machine is traveling forward, or what amounts to the same, when it is moving against a lateral wind. Further, it becomes difficult 20 to regulate the altitude and the landing of the machine, for these depend solely upon the speed of rotation of the sustaining propellers and hence upon the opening of the gas inlet.

25 My invention relates to a device whereby all these drawbacks will be obviated. It consists in principle in the addition to the helicopter of a certain even number of small auxiliary propellers with vertical 30 shaft and variable pitch, termed "evolution propellers", which rotate in pairs in opposite directions, and are driven from the main shafting or by a separate engine. The pilot makes use of devices for controlling 35 their angle of incidence, and is enabled to act upon each propeller by means of a special device which will be further described.

40 In principle, the evolution propellers are disposed symmetrically in pairs about the center of gravity of the machine. Flat blades are preferably used, because they are required to operate under positive or negative incidence. The inclination and straightening of the machine may in particular be controlled by a single device which may further control the movements of ascent and of stabilizing as to altitude and descent. On the other hand, as will be further stated, 45 the said single controlling device may also be used to effect steering or orientation of the machine.

50 The appended drawings which are given by way of example illustrate an embodiment of the invention.

Fig. 1 is a diagrammatic perspective view

of a helicopter having a set of auxiliary or evolution propellers.

Fig. 2 is a separate perspective view of the evolution propellers used for the inclination and straightening of the machine.

Fig. 3 shows the details of a device for controlling the incidence of the blades of said propellers.

Fig. 4 is a longitudinal section of said device.

Fig. 5 is a perspective view of the same.

The helicopter is provided for inclination and straightening purposes with four like evolution propellers E_1, E_2, E_3, E_4 disposed

70 at the vertices of a square whose center is at C. The angle of incidence of the said evolution propellers is controlled by the pairs of wires $f_1 f'_1, f_2 f'_2, f_3 f'_3, f_4 f'_4$; said wires are disposed upon sheaves $g_1 g'_1, g_2 g'_2, g_3 g'_3, g_4 g'_4$, mounted on the tube T, Figs. 3 to 5, and proceed within the said tube, being attached to a sliding member T', mounted on a control rod t, at the points

75 1, 2, 3, 4. The said tube is pivoted by means of a ball-and-socket joint S having a fixed center O; the member t' is slideable within the tube T. With the said tube in the fixed position, should the sliding member be moved longitudinally in the upward

80 direction this will cause the device to draw by the same amount upon the wires f'_1, f'_2, f'_3, f'_4 and to slacken the wires f_1, f_2, f_3, f_4 in like manner, so that the pilot can impart

85 to the four propellers variations of incidence having the same magnitude and direction. But if the tube T is inclined for instance in the direction S', Fig. 4, the wires $f_1 f'_1$ will be stretched and the wires

85 90 $f_3 f'_1$ released, so as to effect the differential control of the two propellers E_1, E_3 , i. e. they will be given variations of incidence of equal value and in opposite directions.

95 The principle of my invention thus becomes clearly apparent. With the machine in equilibrium during the flight, the pilot controls the rise and descent by the sliding of the rod t; he controls the inclination and straightening of the machine by inclining the whole aggregate tT upon S, i. e. about

100 105 the center O, in the convenient direction.

These two operations can be performed simultaneously, and by mounting upon t a hand wheel V the pilot can even effect the steering of the machine; it is simply necessary to dispose upon the tube T a revoluble

110 support, for instance a fork having the two

arms B_1 , B_2 and loosely revoluble in a socket T^1 secured to T ; the ends of said arms e_1 , e_2 are situated upon a straight line passing through the center of the sphere S . The movement of rotation of the fork B_1 , B_2 on the axis XX is combined by suitable means with the rotation of the said hand wheel on the same axis.

- Fig. 5 clearly indicates a theoretical solution of this question. B_1 , B_2 carries a toothed quadrant n engaging a pinion n^1 keyed to the shaft a ; on the said shaft is mounted a second pinion a^2 engaging a toothed ring c . The latter is rotated by the hand wheel by means of a sliding member V^1 such as a long key, fork or the like. The hand wheel turns about t but without actuating it, and can only move the same in the direction XX^1 .
- In this event the wires d_1 , d_2 (steering control wires) will only be lengthened or shortened when the hand wheel is turned on its axis; all the other movements of the wheel (for rising, descent or inclination) will in the first two cases produce no motion of e_1 and e_2 , and in the latter case will raise one of the points e_1 or e_2 whilst the other will be equally lowered.

The wires d_1 , d_2 control the steering of the machine, which may be carried out by the surfaces D mounted rearwardly of the tractive propeller, or by the secondary evolution propellers E'_1 , E'_2 with horizontal axis and variable incidence.

Obviously the principle of the invention will not depend upon the execution of the various details, but is based upon the use of auxiliary propellers in any suitable number, and preferably an even number, so disposed as to provide for the rise and descent of the machine as well as the inclination and the straightening, by means of the single central controlling device, which is operated solely according to the natural reflex movements of the pilot.

To the said device I may also add the steering control, so that the pilot can execute all the operations without handling any other control device except the hand wheel V actuating the rod t .

It is evident that the principle of the invention will remain the same if instead of employing two like propellers per pair, use is made of unequal propellers mounted at different distances from the center of gravity, or further, if a somewhat larger propeller is combined with two or more smaller propellers having the same total effect as the former. The principle of the invention will not be modified for this reason. The only drawback in the use of unequal propellers consists in the production of unequal couples of "antirotation," so that the whole machine frame would turn about, and also the production of involuntary vertical com-

ponents when controlling so as to incline or straighten the machine.

It should be observed that even with the use of like propellers and equal lever arms, a resultant couple acting against the rotation may be produced, and such will be the case for example when the pilot operates by drawing upon the rod t and inclining it at the same time. One propeller of a given pair will thus have a resistance which is not compensated by the resistance of the other, so that it becomes necessary to counteract the effect of "antirotation." But this may be readily carried out, if the machine comprises evolution propellers with horizontal shaft, by turning the steering hand wheel controlling the same, and the wheel may also serve to control the deflecting planes disposed behind the auxiliary propellers. During the flight, the action of the steering rudder will be sufficient.

To recapitulate, my invention consists in the addition to the arrangement which is capable of sustaining the helicopter, of a suitable number of auxiliary propellers with variable and reversible incidence, which are controlled by a central device providing for addition and subtraction of ascensional efforts, as well as effects of inclination and straightening of the machine. The controls may be separate or disposed in the shape of a common controlling device which may also comprise the controls for steering, turning of the machine, or resistance to the "antirotation." In the last two cases, a certain number of the evolution propellers will have horizontal or oblique shafts, such as E'_1 and E'_2 , Fig. 1, or I may also employ deflectors placed behind the propellers such as d'_1 , d'_2 , Fig. 1, or like correcting means which are disposed below the evolution propellers or below the main sustaining arrangement.

In its widest application, my said apparatus can be employed, without requiring the pilot to remove his hands or to make use of his feet, for the various operations of rise, descent, systematic inclination or straightening, and steering of the helicopter.

While any suitable means may be employed for sustaining the helicopter I preferably employ a main propeller whose vertical axis passes through the center of gravity of the machine.

Claims:

1. In a helicopter apparatus, the combination of a main propeller for sustaining the apparatus in the air, and whereof the axis passes through the center of gravity of the apparatus, a plurality of auxiliary propellers in constant rotation during the operation of the apparatus, and disposed symmetrically in pairs, and in different planes about the axis of the main propeller and comprising flat blades whose incidence can

be varied and reversed, the propellers of each pair rotating in contrary directions, a single central lever pivoting in all directions about a center of oscillation, means 5 for varying the incidence of the blades of the said auxiliary propellers, said means being so connected with the said central lever that the movement of the latter in a given direction will vary the incidence of 10 the blades of a given pair of auxiliary propellers.

2. A helicopter comprising in combination means for sustaining the machine in the air, a plurality of auxiliary propellers 15 wherein the incidence of the blades can be modified or reversed, a tube pivoting in all directions about one of its points, a sliding member slidable within the said tube, pairs of wires attached to said sliding member 20 and extending longitudinally through the tube, the two wires of each pair being attached to one of the said auxiliary propellers and adapted to modify the incidence of the respective blades when the said sliding member is displaced in the tube, sheaves 25 mounted on the said tube for guiding the said wires when proceeding out of the tube, the two sheaves corresponding to a given pair of wires and to a given propeller being situated on opposite sides of the said sliding member, a controlling rod secured to the said sliding member and extending through the tube and outwardly of the same, a fork loosely revoluble upon the said tube, the ends of the arms of said fork being situated upon a straight line passing through the pivoting center of the tube, controlling means for rotating the said fork, 30 a pair of wires attached to the ends of the fork and secured to the respective auxiliary propellers wherein the incidence of the blades can be modified or reversed, said controlling means being likewise connected with said controlling rod whereby the latter shall be movable solely in the longitudinal direction.

3. A helicopter comprising in combination means for sustaining the machine in the air, a plurality of auxiliary propellers 35 wherein the incidence of the blades can be

modified or reversed, a tube pivoting in all directions about one of its points, a sliding member slidable within the said tube, pairs of wires attached to said sliding member and extending longitudinally through the tube, the two wires of each pair being attached to one of the said auxiliary propellers and adapted to modify the incidence of the respective blades when the said sliding member is displaced in the tube, sheaves 40 mounted on the said tube for guiding the said wires when proceeding out of the tube, the two sheaves corresponding to a given pair of wires and to a given propeller being situated on opposite sides of the said sliding member, a controlling rod secured to the said sliding member and extending through the tube and outwardly of the same, a fork loosely revoluble upon the said tube, the ends of the arms of said fork being situated upon a straight line passing through the pivoting center of the tube, controlling means for rotating the said fork, 45 a pair of wires attached to the ends of the fork and secured to the respective auxiliary propellers wherein the incidence of the blades can be modified or reversed, said controlling means being likewise connected with said controlling rod whereby the latter shall be movable solely in the longitudinal direction.

In testimony that I claim the foregoing as my invention I have signed my name in 50 presence of a subscribing witness.

ETIENNE OEHMICHEN.
